CLAIM

The ornamental design for a mobile phone shell with photographing handle as shown and described.

DESCRIPTION

2.1 is a front view of a first embodiment of a mobile phone shell with photographing handle, showing the new design;

2.2 is a back view thereof;

2.3 is a left view thereof;

2.4 is a right view thereof;

2.5 is a top view thereof;

2.6 is a bottom view thereof;

2.7 is a rear perspective view thereof;

2.8 is a front perspective view thereof;

3.1 is a front view of a second embodiment of a mobile phone shell with photographing handle, showing the new design;

3.2 is a back view thereof;

3.3 is a left view thereof;

3.4 is a right view thereof;

3.5 is a top view thereof;

3.6 is a bottom view thereof;

3.7 is a rear perspective view thereof; and

3.8 is a front perspective view thereof.

(Continued)

The broken lines in the reproductions depict portions of the mobile phone shell with photographing handle that form no part of the claimed design.
